UNITED STATES PATENT OFFICE.

HAMMOND J. EVANS, OF HAMPTON, CANADA.

VINE-CUTTER.

SPECIFICATION forming part of Letters Patent No. 548,530, dated October 22, 1895.

Application filed May 23, 1895, Serial No. 550,428. (No model.)

To all whom it may concern:

Be it known that I, HAMMOND J. EVANS, of 5
Hampton, in the Province of New Brunswick
and Dominion of Canada, have invented a
new and Improved Vine-Cutter, of which the
following is a full, clear, and exact descrip-
tion.

My invention relates to an improvement in
machines for cutting vines; and the object of
10 this invention is to provide a machine adapted
to cut off parts of any creeping vine, but is
particularly adapted for use in trimming or
cutting off runners of strawberry-vines, in order
15 to promote the strength of the plant; and
a further object of the invention is to provide
a machine of the above character which will
be simple, durable, and economic, and capable
20 of being carried close to the plant, cutting
off desired portions without injuring remain-
ing portions; and, furthermore, to provide a
means whereby the cutters may be adjusted,
and whereby ready access may be obtained to
25 said cutters for the purposes of sharpening or
cleaning when necessary.

25 The invention consists in the novel con-
struction and combination of the several
parts, as will be hereinafter fully set forth,
and pointed out in the claims.

Reference is to be had to the accompanying
30 drawings, forming a part of this specification,
in which similar characters of reference indi-
cate corresponding parts in both the figures.

Figure 1 is a longitudinal vertical section
35 through the machine, and Fig. 2 is a plan
view thereof.

In carrying out the invention the body of
the machine is made to terminate at its for-
ward end in a finger 10 of substantially the
40 same shape as the finger of a sickle-bar in a
harvesting-machine, the bottom of the finger
being adapted to travel on the ground, and
the said finger is inclined upon its upper face
45 in a forwardly and downwardly direction and
beveled at its sides in opposite directions.

The body is preferably made integral with
the finger, and where it connects with the
said finger is carried upward, and from thence
in a rearwardly direction, whereby the body
50 is of more or less angular construction. The
body and finger-bar are made in two sections
a and a', divided longitudinally, and in the
rear portion of the finger-bar and forward

portion of the body a longitudinal opening 11
is produced at the center or where the two
parts are connected, and this opening is pref- 55
erably considerably wider at the bottom of the
finger and body than at the top, in order that
a proper clearance may be obtained for any
particles that may adhere to the cutters, the
said cutters being located within the opening 60
11. The two sections of the body and finger
are connected by bolts 12 or their equivalents,
and a handle 13 is secured in any suitable or
approved manner in the rear portion of the
body, the said handle being preferably curved 65
upwardly and rearwardly to facilitate the ma-
nipulation of the machine.

In the upper portion of the body an axle 14
is secured, upon which two ground-wheels 15
and 16 are carried, the ground-wheel 15 at 70
the left-hand side of the machine being pro-
vided with an internal gear 17 and is fast on
the axle, while the opposing ground-wheel 16
may be and preferably is of the ordinary con-
struction, and is removable from the axle. 75

At or near the central portion of the open-
ing 11 in the body and finger of the machine
a shaft 18 is journaled. This shaft extends
beyond the left-hand side of the body, and at
its extended end a pinion 19 is secured, mesh- 80
ing with the internal gear 17 of the ground-
wheel 15, whereby the shaft receives its mo-
tion from the movement of this ground-wheel.

A stellated cutter-wheel 20 is secured on the
shaft 18 within the opening 11 of the machine, 85
and the teeth of this wheel are sharpened, be-
ing beveled in direction of the left-hand side
of the wheel, as illustrated in Fig. 1, and in
the left-hand wall of the opening 11, at or
near the forward portion of the same, a recess 90
21 is made, in which a cutter 22 is adjustably
secured, the said cutter being provided with
openings 23 and adjusting-screws 24, passed
through the said openings, holding the cutter
in place. The upper edge of this cutter 95
is made to extend upward substantially flush
with the upper surface of the finger and fin-
ger-bar of the machine, and is beveled down-
wardly in direction of the left-hand side of
the machine, and the cutting of the material ^{rec}
is effected by the cutting-edges of the stellated
wheel passing the sharpened edge of the sta-
tionary cutter 22.

It is obvious that the stationary cutter may

be adjusted or removed, as occasion may demand, by simply removing the ground-wheel 16 and separating the two sections of the finger or finger-bar, together with the sections 5 of the body.

In the operation of this machine as it is advanced the vines will be taken up by the finger-bar or finger and will be directed between the cutters, where the vines will be 10 quickly and cleanly severed.

In the event the vines might be damaged by the passing of the machine in its ordinary shape after desired parts have been cut, or when it is necessary to cut close up to the 15 body of the vine, the wheel 16 is removed, bringing the cutters near the trunk and precluding the possibility of injuring the standing portion of the vine after the surplus material has been removed.

20 This machine is exceedingly simple, it is durable, and it is economic, and it may be conveniently operated. Furthermore, it will sever the tendrils or other portions of a vine in a manner which will prevent as far as possible 25 the bleeding of the vine.

Having thus described my invention, I claim as new and desire to secure by Letters Patent—

1. A vine cutter, comprising a body portion 30 formed with a forwardly extending pointed finger bar having a lower flat side to travel along the ground and inclined or curved on its upper side from its side edges to its longitudinal center, a longitudinal central vertical slot at the juncture of the body and finger bar, a stellated cutter wheel journaled therein, a stationary cutter mounted in the side of the slot at the forward end thereof with its cutting edge at the upper side of the finger bar for co-operation with the teeth or arms 35 40

of the cutter wheel and supporting wheels in rear of the cutter wheel and geared thereto, substantially as described.

2. A vine cutter, comprising the pointed finger bar having an upwardly and rearwardly 45 extending body-forming portion at its rear end, the whole being divided on its central vertical longitudinal line into two sections secured removably together face to face, a vertical slot being formed in the rear end of the 50 finger bar and the adjacent body portion, and a second inclined handle receiving slot being formed in the rear end of the body portion by registering recesses in the inner faces of its two sections, a rotary stellated cutter wheel 55 journaled in the first named slot and operating in connection with a fixed cutting edge at the upper side of the finger bar, and the ground wheels, one of which is geared to the rotary cutter, substantially as described. 60

3. In a machine for cutting vines, and for similar purposes, the combination, with a body and a finger bar or finger projected forwardly therefrom, the body and finger bar being provided with a longitudinal opening and constructed in sections, and ground wheels supporting the said body and finger bar, of a rotating stellated cutter mounted to revolve in the opening in the body and finger bar, being driven from one of the ground wheels, and an 70 adjustable cutter placed in a wall of the said opening in front of the rotating cutter, whereby a shear cut is obtained, and ready access may be secured to either cutter for purposes of sharpening or for other purposes, substantially as described. 75
